UNITED STATES PATENT OFFICE.

JOHN J. REILING, OF PHILADELPHIA, PENNSYLVANIA, ASSIGNOR TO GEORGE D. ELLIS & SONS, INCORPORATED, OF PHILADELPHIA, PENNSYLVANIA, A CORPORATION OF PENNSYLVANIA.

MEASURING FUNNEL.

Application filed January 6, 1925. Serial No. 763.

My invention relates to funnels which are adapted for the filling of the gasoline tanks of automobiles and also for the measuring of any liquid into a container of any kind 5 or character.

The general object of the invention is to provide a funnel having the capacity of holding a considerable quantity of a liquid and also having means whereby when a certain 10 or measured quantity of the liquid has been placed in the funnel the closure of the funnel opening may be opened to permit the escape of the liquid from the funnel into a container.

15 It is also an object of the invention to provide an improved construction or means for controlling the opening or outlet of the funnel.

Other objects and advantages of the invention 20 will be pointed out in the detailed description thereof which follows or will be apparent from such description.

In order that the invention may be understood readily and its practical advantages 25 fully appreciated reference may be had to the accompanying drawing in which I have illustrated one form of a convenient embodiment thereof. However, it will be understood that changes in the details of construction 30 may be made within the scope of the claims without departing from the spirit and scope of the invention.

In the drawing Fig. 1 is a vertical central 35 section of a funnel embodying the invention;

Fig. 2 is a similar view showing certain of the parts thereof in different positions from what they are shown in Fig. 1;

Fig. 3 is a transverse sectional view taken 40 on the line 3—3 of Fig. 1; and

Fig. 4 is a view in side elevation of a fragmentary portion of the funnel structure.

Referring to the drawing:

1 designates an upper cylindrical portion and 2 a lower truncated cone shaped portion. 45 In the construction as shown these two portions or parts are made of separate members secured together as indicated at 3 but if desired the portion of the funnel composed

of these two parts or portions may consist of a single integral metal sheet pressed into 50 the form shown.

The lower end of the truncated cone shaped portion 2 terminates in a tubular portion 4 which extends into the upper end of a short tubular section 5 and is secured 55 thereto by means of rivets 6 or otherwise.

A plate 10 is mounted in the truncated cone shaped portion 2 near the lower end thereof. This plate extends crosswise of the funnel and its outer edges are secured by 60 soldering or in any other suitable manner in the walls of the portion 2. The said plate is provided with a central outlet opening 11 and the portion thereof surrounding said opening constitutes a seat 12 for the valve 65 15. The lower side of the said valve is provided with a washer 16 of suitable material which is adapted to contact with the valve seat 12 and close the opening 11. The valve 15 is provided with a number of openings 17, three being employed in the construction, as illustrated, through which supporting pins 18 extend. The lower ends of these pins are screw threaded and engage screw threaded openings 20 in the plate 10. 75

Coiled springs 21 are mounted upon the pins 18 above the valve 15. The lower ends of these springs rest upon the valve 15 while the upper ends thereof contact with the underside of the heads 22 at the upper ends of the 80 said pins. Normally the valve 15 is yieldingly held against the seat 12 upon the valve plate 10 by the springs 21.

For the purpose of elevating the valve 15 to open the same a rod 25 is provided the 85 lower end of which is connected by means of a nut and bolt 26 to the valve 15. The said nut and bolt also operate to retain the washer 16 in place upon the lower side of the said valve. The upper end of the rod 25 90 is pivotally connected to the inner end of a lever 27 which is pivoted intermediate its ends at 28 to a lug 29 secured to the upper edge portion of the funnel structure. The upper end of the lug 29 projects above the 95 upper edge of the funnel structure while the

lower end thereof terminates a short distance below said upper edge. The lower end of the said lug is undercut as indicated at 30 whereby it is adapted to engage the 5 lower side 31 of an oblong metal loop catch or engaging member 32 the upper end of which is pivotally connected with the lever 27 at a point beyond or outside of the pivot 28. When the outer end of the lever 10 27 is depressed so as to turn the said lever about its pivot to effect raising or lifting of the inner end of the said lever the rod 25 is correspondingly elevated and effects elevation or lifting of the valve 15 into open position 15 whereby any liquid which may be present in the funnel is or may be discharged therefrom. Upon depressing or lowering the outer end portion of the handle 27 the lower end of the loop or catch 32 swings 20 underneath the lower end of the projection 29 and engages with the undercut surface 30 thereof. By such engagement of the loop catch 32 with the lower end of the projection 29 the valve 15 is held in open position 25 until the said loop catch is released. Upon such release the valve is automatically closed by the expansion of the coiled springs 21 which obviously are compressed upon the pins 18 when the said valve is elevated or raised into 30 open position by the manipulation of the lever 27 as previously described.

If it is desired to measure a certain amount of liquid into a container the funnel should be provided with means whereby 35 the amount of liquid therein may be easily ascertained and determined. To that end I have provided a groove 35 upon the inner side of the funnel a short distance from the upper edge thereof and have also provided 40 a pointer or marker 36 the lower end of which terminates at the middle of the bottom of the said groove. There may be one, as shown, or more of these quantity or volume indicators upon the inner side of the 45 funnel structure and these indicators may indicate a quantity of two, three, four or five gallons or any other quantity as may be desired. It will be understood of course that the size of the funnel preferably should 50 correspond to the volumes or quantities desired to be measured into a container at a single operation.

In order to facilitate the discharge of the liquid into a container I have provided 55 means upon the tubular outlet portion 5 for resting upon a portion of the container to support the funnel while the valve 15 is in open position and while the liquid is being discharged therefrom into the said container. It will be understood that the tubular outlet 5 must or should be of a size 60 such as to permit it to project into the opening of the container into which the liquid is to be discharged. The support consists of 65 an annular member having vertical and

horizontal flanges 38 and 39. The tubular outlet 5 projects through the opening of the said member and is secured thereto by means of rivets 40 which extend through the vertical flange 38. Instead of using an annular member such as is shown it will be understood that any other means suitable for the purpose may be secured to the lower end portion of the funnel structure so that it may rest upon portions of the container 70 adjacent the opening through which the liquid is being discharged thereinto in order to support the said funnel during the time that such discharge is taking place. For the purpose of producing a finished and 75 complete structure I have provided a truncated cone shaped member 42 the lower edge of which contacts with the upper edge of the flange 38 while the upper edge thereof contacts with the portion 2 of the funnel structure near its lower end. The edges of the opposite ends of the member 42 are soldered in place so as to retain it immovably in position and so as to strengthen the 80 structure and prevent distortion or breakage 85 thereof.

It will be seen that by my invention I have provided a measuring funnel in which the measuring of a given or desired quantity of liquid into a container is greatly 90 facilitated.

Having thus described my invention what I claim and desire to secure by Letters Patent is:

1. A measuring funnel comprising, in 100 combination, a valve for closing the outlet opening thereof, vertical pins located above the valve seat upon which said valve is slidably mounted, yielding means mounted upon said pins for holding said valve in closed position, means for opening said valve, and releasable means for holding the valve in open position during the period in which the liquid is being discharged from the funnel into a receiver.

2. A measuring funnel comprising, in combination, a valve for opening and closing the outlet opening, means for slidably supporting the said valve, yielding means which hold and tend to hold the said valve 105 in closed position, said means being mounted upon the said supporting means, means operable from the exterior of said funnel for opening the said valve, and releasable means for holding the last mentioned means in position to retain the said valve in open position while the liquid in the said funnel is being discharged therefrom.

3. A funnel comprising a tapered lower end portion and a plate located interiorally of the funnel adjacent the lower end thereof of which plate extends transversely of the funnel and its outer edges being secured to the wall of the funnel and the said plate having an opening therethrough, pins pro- 110 115 120 125 130

jecting upwardly through the said plate, a valve slidably mounted on the said pins and adapted to contact when in closed position with the portion of said plate surrounding 5 said opening, yielding means located on the said pins above the said valve and exerting downward pressure on the latter for holding the same in closed position and means

for lifting the said valve from its seat to open the said opening.

In testimony that I claim the foregoing as my invention, I have hereunto subscribed my name this 29th day of December, A. D., 1924.

JOHN J. REILING.
